UNITED STATES PATENT OFFICE.

MAX ROSENBLATT, OF NEW YORK, N. Y., ASSIGNOR TO JOHN F. MEYER, OF CHICAGO, ILLINOIS.

COIN-CONTROLLED APPARATUS.

Application filed June 20, 1925. Serial No. 38,406.

My invention relates to a novel and improved apparatus preferably controlled by a coin or the like and which will permit a predetermined number of revolutions of a shaft by a motor, at the end of which release of the coin will be caused, together with stoppage of the mechanism. The principal object of the invention is to provide a device of the above character which may be cheaply and efficiently manufactured and which will perform its operations in a positive and effective manner. A further object is to provide a device for use with a coin controlled mechanical dice shaker, and which may be employed as a fortune teller.

In the accompanying drawings in which I have shown a selected embodiment of my invention;

Fig. 1 is a perspective view of my mechanism as embodied in a cabinet.

Fig. 2 is a vertical sectional view through the cabinet shown in Fig. 1.

Fig. 3 is a detail view of one of the dice cups.

Fig. 4 is a section on the line 4—4 of Fig. 2.

Fig. 5 is a section on the line 5—5 of Fig. 2.

Fig. 6 is a section on the line 6—6 of Fig. 5.

Fig. 7 is a section on the line 7—7 of Fig. 5.

Fig. 8 is a section on the line 8—8 of Fig. 2.

Fig. 9 is a section on the line 9—9 of Fig. 8.

Referring now to the drawings, the number 1 designates any suitable cabinet in which my invention may be desired to be incorporated, the cabinet comprising a base 2, above

which is disposed a compartment 3 closed by a door 4 and having at its top a base plate 5. The back wall 6 of the cabinet extends upwardly and forms the rear wall of a chamber 7 within which is disposed the operating mechanism of the device. This chamber is

closed in front by a glass panel 8, which enables inspection and observation of the mechanism.

In the base plate 5 and in front of the panel 8 is disposed a coin slot 9 registering with a coin chute 10 disposed on the inner surface of the door 4. Extending through openings in the walls of the coin chute are a pair of fingers 11, spaced apart a sufficient distance to support a coin thereon and prevent its passage through the chute. The fingers are mounted on a rock shaft 12 supported on an arm 13 which in turn is pivotally supported

on a second rock shaft 14 mounted in brackets 15 on the base plate. The arm 13 is normally held in position with the fingers extending into the chute by means of a spring 16, as plainly shown in Fig. 2.

Mounted adjacent one wall 17 of the cabinet is a suitable clock mechanism 18 comprising a spring motor 19^a and gearing causing rotation of a shaft 19 supported in suitable bearings in the clock work and in the brackets 20. The gearing includes the gear 21 which also drives further gearing driving a shaft 22 upon which is mounted the brake 23, consisting in this instance of a plate having a notch 24 in one edge thereof, as indicated in Fig. 5.

Mounted on the end of the rock shaft 12 is a link 25 pivoted to a double lever having one arm 26 adapted to engage the brake 23 and to pass through the notch 24 upon revolution of the brake. The other arm 27 is secured to a member 28 mounted on a pivot 29 secured to the frame of the clock work. The arm 27 is provided with an extension 30 beyond the member 28 and bent at right angles thereto and forming a pawl riding upon the cam 31. As best shown in Fig. 7, this cam is provided with one recess 32, the remainder of the periphery thereof being circular in form and grooved, as shown at 33 (Fig. 5) to retain the end of the extension 30 therein, this extension forming a pawl co-operating with the cam.

The rock shaft 14 is provided with an arm 34 held by the spring 16 in engagement with the hub 35 of the cam 31. Mounted on the cam is a pin 36 arranged to contact with the arm 34 and lift the same against the action of the spring 16.

The operation of the mechanism thus far described is believed to be plain from the description, but it will be briefly summed up here. The normal position of the parts is shown in Figs. 1 and 2. Upon depositing a coin in the slot 9, the fingers 11 are depressed from the position shown in full lines in Fig. 2, downward movement being limited by the walls of the openings in the chute 10. This movement will cause the fingers to rock the shaft 12 upon which they are secured and through the link 25 will cause the arm 26 to be raised out of engagement with the brake 23 and thus release the clock work, causing

rotation of the shaft 19 in a counterclockwise direction, as viewed in Figs. 2, 6 and 7. During this rotation of the shaft the pawl 30 will leave the recess 32 and ride on the circular part of the periphery of the cam 31, thus holding the arm 26 out of engagement with the brake 23 until the shaft 19 has completed one revolution, when the pawl will snap back into the recess due to its own weight and the weight of the other parts connected thereto, thus bringing the arm 26 back into position wherein it will engage the brake and stop operation of the clock work. The notch 24 in one edge of the brake 23 is provided for the purpose of permitting the arm 26 to move into and out of position without being interfered with by this edge of the brake.

The coin remains in position on the fingers thus holding the arm 26 out of engagement with the brake while the pawl is riding on the periphery of the cam. The coin is then released by engagement of the pin 36 with the arm 34, this engagement being shown in Fig. 7, and causing rocking of the shaft 14 to move the fingers 11 backwardly to the position shown in dotted lines in Fig. 2. The coin is then permitted to pass through the chute to the compartment 3 in which a suitable drawer may be arranged, if desired. As soon as the pin 36 passes out of engagement with the arm 34, the spring 16 will return the arm to its initial position, and the fingers 11 into position to receive another coin. In order to avoid any possibility of the fingers 11 being depressed to such an extent that they will not re-enter the openings in the walls of the chute, there is provided a shelf 37 projecting inwardly and upon which the fingers rest.

Rotation of the shaft 19 may be employed for any desired purpose, but I have shown it herein as being employed for operating a mechanical dice shaker. This shaker in the present embodiment consists of two cups 38 connected by a web 39, the outer surfaces of the cups being provided with hubs 40 whereby the device may be secured on the shaft 19. Pivoted to the cups are trays 41 connected by a web 42 and provided with rearwardly extending arms 43 to receive the pivot 44 and to connect the trays to a counterweight 45. The pivot 44 passes through the arms 43 and the ears 46 on the cups. The normal position of the dice shaker is shown in Figs. 1, 2 and 5, wherein it will be seen that the trays are maintained in a substantially horizontal position by means of the counterweight 45. As the shaft 19 is rotated the trays remain in a substantially horizontal position until the cups come in contact therewith and thus close the receptacles formed by the cups and the trays. The entire device continues to rotate until the trays reach a position substantially 180° from that shown in Fig. 2, when the counterweight will cause them to drop in front of the cups, and when the trays and cups approach the po-

sition shown in Figs. 1, 2 and 5, the dice contained in the cups will slide into the trays.

The mechanical dice shaker described above may be used for a variety of purposes, but I prefer to employ it with a coin controlled mechanism, such as described herein, to operate as a fortune teller, or the like. For this purpose I have shown mounted on the exterior of the cabinet a frame 47 carrying a sign 48 upon which are arranged a plurality of legends 50, each corresponding to a given number. The sum of the numbers shown by the dice may be noted and the corresponding legend on this sign may be considered as the fortune. When the device, on the other hand, is intended for use with one of the many games in which dice are used, such a parcheesi and backgammon, the coin controlled feature may be dispensed with entirely and replaced by other means, or it may be operated by inexpensive checks which may be used over and over again.

It will be noted that the members 13 and 25 are supported from the common rock shaft 14 and that the lower end of the member 25 is connected directly with the shaft 12 upon which the fingers 11 are mounted, thus lessening the number of parts required and better insuring uniformity of movement in operation. The free end of the stop arm 13^a contacts with the inner wall of the chute member 10 and serves as a stop to prevent the free ends of the fingers 11 from contact with the wall of the chute. The stop arm 13^a and the fingers 11 are carried by the same member and move in unison as seen in Fig. 2.

From the above it will be apparent that I have provided a novel and improved apparatus to control the operation of the shaft, and which in turn may be controlled by a coin or the like and which may be employed with a wide variety of devices, for various purposes. The device is extremely simple in construction and operation and easily operated by a motor, such as a spring motor, which can be easily rewound as by a handle 49. When employed with the frame 47 and sign 48 the device forms a fortune telling means which furnishes a great deal of amusement.

I am aware that changes in the form, construction and arrangement of parts may be made without departing from the spirit and without sacrificing the advantages of the invention and I reserve the right to make all such changes as fairly fall within the scope of the following claim:

I claim:

In a device of the class described, a cabinet having a coin chute, a rock shaft mounted in said cabinet, an arm pivoted to said rock shaft, a second rock shaft on said arm, a horizontal shaft, clock mechanism to rotate said horizontal shaft, means holding said horizontal shaft against rotation, a cam on said horizontal shaft, a link connected to said second

rock shaft and having an arm engaging said cam, fingers on said second rock shaft extending into said coin chute and adapted to be moved by a coin, means operated by said fingers to release said holding means and permit rotation of said horizontal shaft, an arm on said first rock shaft adapted to be operated

by a pin on said cam for withdrawing the fingers from said coin chute, means for returning the fingers to normal position in the chute, and an inwardly projecting shelf on said coin chute to guide the fingers during movement thereof.

MAX ROSENBLATT.
